UNITED STATES PATENT OFFICE.

JOHN O'FALLON CLARK, JR., OF ST. LOUIS, MISSOURI, ASSIGNOR TO AMERICAN MAN-
GANES STEEL COMPANY, OF AUGUSTA, MAINE, A CORPORATION OF MAINE.

DIPPER-TOOTH.

1,176,275.

Specification of Letters Patent. Patented Mar. 21, 1916.

Application filed August 25, 1913. Serial No. 786,358.

To all whom it may concern:

Be it known that I, JOHN O'FALLON CLARK, Jr., a citizen of the United States, and a resident of St. Louis, in the State of Missouri, have made and invented certain new and useful Improvements in Dipper-Teeth, of which the following is a specification.

My invention relates to teeth designed for use with the dippers or buckets of excavating, dredging, digging, and similar machines, and particularly to that kind or class of teeth in which a permanent supporting member or base is provided to the end of which a detachable tooth point may be secured, so that when the point becomes worn out in service it may be replaced by a new point and without discarding the base portion of the tooth.

The object of my invention is to provide an improved construction of detachable and renewable tooth point of the type above referred to, and an improved construction of base adapted to support the detachable point, all as hereinafter described at length and claimed in the concluding claims.

The drawing accompanying and forming a part of this application illustrates the preferred embodiment of my invention, although it will be understood that my invention includes such variations and modifications of the particular tooth point and base illustrated as will be obvious to those skilled in the art to which my invention relates.

In the drawing: Figure 1 is a view illustrating a portion of my improved dipper tooth in side elevation, the same comprising a permanent base and a detachable and renewable point; Fig. 2 is a view illustrating the parts of the tooth separated from one another, and in perspective; and Fig. 3 is a view illustrating the point only of the tooth in perspective, as seen from another position.

Referring to the drawing, the reference numeral 4 designates the permanent or base portion of my improved dipper tooth, the same being commonly secured to the inner face of a dipper body and having a recess 5 designed to fit over the edge or lip of the dipper and a jaw 6 which extends a short distance along the outer surface and toward the bottom of the dipper body, although these features are not involved in my invention.

The outer or free end of the base of my improved tooth is so shaped as to provide two inclined seats 7, which merge with one another and form a triangular point support to which the detachable and renewable point 8 of the tooth is secured, and from which support it may be readily removed when worn out, and an unworn point substituted therefor, thus rendering it unnecessary to renew the base when the point has been worn to such an extent as to be unserviceable. While the point support is referred to herein as triangular in form it will be seen that it departs from a true triangle in that its apex is rounded, and I use the term in a general sense to indicate a point support of tapering form, and intend to include a point support in which the seats themselves may be slightly curved, as is sometimes the case in practice.

The inclined seats 7 are provided each with a centrally located longitudinally extending recess 9 which recesses increase in depth as they recede from the apex of the triangular point support, as shown in Figs. 1 and 2 of the drawing and which recesses are separated from one another by a longitudinally extending web 16; and two transversely extending holes 10 are provided, which holes intersect the recess 9 and are adapted to receive bolts, pins, or similar elements for holding the detachable point in place as will hereinafter appear.

The detachable point portion of my improved dipper tooth is bifurcated as shown, to thereby provide two sides or arms 11, the inner surfaces of which arms are inclined to correspond with the inclination of the seats upon the base and which inner surfaces merge with one another to thereby provide a triangular opening which fits over the triangular point support of the base hereinbefore referred to and as will be understood from Fig. 1. Each of the arms 11 is provided with a centrally located securing lug 12 upon its inner surface and which lugs are provided each with a hole 13, which holes come opposite the holes 10 when the point is in place upon the base so that a pin or bolt may be inserted in the holes to hold the point in place. The lugs 12 thus project toward one another; and they are preferably located adjacent the rear ends of the arms so that they will lie adjacent the rear portions of the recesses 9 into which they enter as the

point is put in place by moving it longitudinally along the center line of the base, as will be understood.

Means are preferably provided for preventing lateral movement of the point relative to the base; such means being shown as comprising a central recess 14 formed in the point at the apex of the triangular opening therein, and a projection 15 formed at the apex of the triangular point support of the base which projection enters into the recess 14 when the point is in place upon the base.

In the drawing the form of the triangular point supporting portion of the base, and of the triangular opening in the point, and the relative location of the securing lugs and holes, are such that the point may be reversed upon the base to thereby secure more uniform wearing away of the extremity of the point and of the two arms thereof; although my invention is in no way limited to dipper teeth in which the detachable point is also reversible.

Having thus described and explained my invention, I claim and desire to secure by Letters Patent:

1. A base for a dipper tooth comprising a body with a forwardly projecting point supporting nose, said nose provided with upper and lower rearwardly extending non-communicating recesses, the transverse web intermediate said recesses providing for the lateral bracing of the nose side walls.

2. A base for a dipper tooth comprising a body with a forwardly projecting point supporting nose, said nose provided with rearwardly extending and deepening upper and lower non-communicating recesses with the bottom walls thereof extending substantially parallel, said recesses defining a transverse web extending between the nose side walls and providing for their lateral bracing or reinforcement, said web projecting beyond the front of said nose.

3. A dipper tooth removable point including rearwardly diverging upper and lower arms, confronting isolated or separated bolt engageable lugs projecting from the inner surfaces of said arms, the meeting portions of said arms provided with a forwardly ex-

tending recess lying directly in front of said lugs.

4. A dipper tooth removable point including rearwardly diverging upper and lower arms, confronting isolated bolt engageable lugs projecting from the inner surfaces of said arms, the meeting portions of said arms provided with a forwardly extending recess lying directly in front of said lugs, said lugs and recess lying in the median plane of said point.

5. A dipper tooth comprising a base with a forwardly projecting nose, said nose provided with rearwardly extending and deepening upper and lower non-communicating recesses, said recesses defining a transverse web extending between and providing for the lateral bracing of the nose side walls, said web projecting beyond the front of said nose; a removable point including rearwardly diverging upper and lower arms, confronting separated bolt-engageable lugs projecting from the inner surface of said arms adapted to receive the said nose web there-between, the meeting portions of said arms provided with a forwardly extending recess adapted to receive and engage the protruding portion of said web, means extending through and engaging the side walls of said nose, detachably engaging said lugs and co-acting with the securing means effected by the protrusion of said web and the receiving recess within the said point for the detachable and rigid securement of said point and base.

6. A base for a dipper tooth comprising a body with a forwardly projecting bifurcated nose, a web connected to and extending between the side walls of the nose, said web extending to the bottom of said bifurcation and beyond the front extremity of said nose.

Signed at Chicago in the county of Cook and State of Illinois this 16 day of August A. D. 1913.

JOHN O'FALLON CLARK, Jr.
